INVENTOR
G. SELBY:
BY Adam E. Fisher
ATTORNEY

UNITED STATES PATENT OFFICE.

GRANT SELBY, OF ST. LOUIS, MISSOURI.

FUSEE AND TORPEDO HOLDING ATTACHMENT FOR RAILROAD-LANTERNS.

1,305,014.

Specification of Letters Patent. Patented May 27, 1919.

Application filed March 5, 1919. Serial No. 280,824.

To all whom it may concern:

Be it known that I, GRANT SELBY, a citizen of the United States, residing in the city of St. Louis and State of Missouri, have 5 invented new and useful Improvements in Fusee and Torpedo Holding Attachments for Railroad-Lanterns, of which the following is a specification, reference being had to the accompanying drawings.

10 This invention pertains to fusee and torpedo holding attachments for railroad lanterns as used by railroad flagmen, or train or trackmen of any kind or character in their work upon or about railroad trains 15 and tracks in the course of protecting or signaling trains, and for like purposes.

The primary object of the invention is to produce an attachment of this character which may be readily applied to, or detached from any ordinary and standard railroad lantern, and which when so attached to the lantern will afford a convenient and efficient receptacle for the fusees and torpedoes used for signaling by railroad men.

20 A secondary object is to provide such an attachment with special hooks or fastenings to facilitate the ready attachment or detachment of the device to the lantern.

25 Another object is to produce such an attachment as will not obscure the light, and a still further object is to provide means for protecting and preserving the fusees and torpedoes against the deteriorating effects of weather and handling, as ordinarily occurs 30 when such signals are unnecessarily exposed.

35 Further, by the use of this attachment the signals are always ready for instant use and at the hand of the operator, and the signals are always kept in their condition of prime 40 efficiency.

With these objects in view, attention is called to the accompanying drawings, wherein

45 Figure 1 is a side elevation of an ordinary railroad lantern properly equipped with my improvement;

Fig. 2 is a top plan view of one of the fusee container tubes with the top cap removed, showing a fusee located therein;

50 Fig. 3 is a cross section taken on the line A—A in Fig. 1, showing how the container tube is fastened to the lantern frame at this point by means of an ordinary swinging hook;

55 Fig. 4 is a similar cross section taken on the line B—B in Fig. 1, showing a special

form of hook used to attach the container tube to the lantern frame at this point, thus giving two vertical and four horizontal points of support; 60

Fig. 5 is a detail, showing a loose band slidingly mounted around each tube, and which may be raised or lowered to adjust the attachment to different styles of lanterns;

Fig. 6 is a front view of the torpedo container, showing the container lid open and revealing the torpedoes located therein. 65

Referring more particularly to the drawings, my invention in its preferred construction, consists in two fusee container tubes 70

as shown at 1 and 2 mounted in vertical alinement with the side bars 3 and 4 of the lantern 5. These fusee container tubes are each provided with telescoping caps 6 and 7 adapted to slide upon and over the upper 75

ends of the said fusee container tubes 1 and 2, respectively, to protect the fusee 8 from the weather, and to more conveniently receive fusees of different lengths. The fusee 80

container tubes 1 and 2 are so as aforesaid 85 detachably mounted from and in alinement with the side bars 3 and 4 by means of an ordinary swinging catch 9 pivoted to the bracket 10 extended from the fusee container tubes 1 and 2, respectively, and adapt-

ed to swing around and engage the side bars 3 and 4 of the lantern 5, and thus sustaining the said tubes against the said side bars at these points. The catches 9 may be extended from sliding bands 22, whereby the catches 90

may be raised or lowered, and are rendered readily adjustable to various forms of lanterns. Complementary to, and as additional means of support for said fusee container tubes, I provide a special form of catch 11, 95

which preferably consists of a length of wire formed spirally with bends 12 and 13, and thus being adapted to engage both the base ring 14 of the lantern 5, and the vertical side bar 3. One of these special catches 11 100

is rigidly attached to the bottom end of each of the fusee container tubes 1 and 2, and when the said tubes are detached and are free from the lantern, the special catch 11 affords means for readily locking the 105

lower ends of said fusee container tubes into place upon the lantern as shown in Fig. 1, by merely turning and twisting the special catch 11 first around the base ring 14, and then up around and back of the vertical side 110

bar 3, thus locking the tube against either lateral or vertical movement. The catch 9

is then swung around and back of the said side bar 3, thus locking the tube against said side bar at a point spaced vertically upward from the lower end of the tube, and affording two vertical and spaced points of support for the tube. Thus the tubes are held securely attached to the lantern, and may be readily detached as desired. Of course, any number of the fusee container tubes may be employed and similarly attached around the lantern frame at spaced distances. These tubes may also be painted a vivid red to heighten the signaling effect of the lantern.

As stated, I provide preferably two of said fusee container tubes as shown at 1 and 2, and upon one of the lower ends of one of said tubes as 2, I rigidly mount the auxiliary torpedo container 15, in such position that the container 15 stands out horizontally to one side of the tube 2, and is extended along the base of the lantern 5. The torpedo container 15 may be riveted to the lower end of the tube 2, or secured in any other suitable manner, so that when the tube 2 is removed from the lantern as aforesaid, the container 15 will likewise follow. The container 15 is preferably of cylindrical construction, and has a hinged lid 16 depending from the hinge 17 and opening outwardly and downwardly, as shown. A spring catch 18 holds the lid 16 closed. The container 15 is adapted to hold six track torpedoes 19. Chains 20 and 21 connect the caps 6 and 7 to the fusee container tubes 1 and 2 respectively.

In use, the operator or trainman carries the lantern always with him. The fusee container tubes each hold a fusee of the ordinary kind adapted for burning upon the track for the purpose of making certain signals, and the torpedo container is adapted to hold about six of the ordinary track torpedoes for the purpose of making the ordinary signals by means of such torpedoes. Thus, the trainman or other operator is always provided with the necessary materials, such as fusees and torpedoes as required in the course of his work, and as long as he carries his lantern with him, he will not be caught without these materials at hand. Likewise, the said materials are kept protected from the weather and handling, thus

preventing deterioration of the same, and so that same are always in condition for effective use. The fusee container tubes being aligned with the side bars of the lantern, there is no obstruction afforded by said tubes to said light. The tubes and container are readily detachable from the lantern when desired for any purpose.

While I have herein described a certain specific manner and method of constructing and assembling the elements of my invention, it is understood I may vary from the same in minor details, not departing from the spirit of my invention, so as best to construct a practical device for the purpose intended, as defined in the appended claims.

What I claim to be new and patentable is:

1. A fusee and torpedo holding attachment for lanterns, comprising two elongated fusee containers with removable caps chained thereto, detachably mounted one each adjacent to and in vertical alignment with the opposite side bars of the lantern; a box-like torpedo container having a hinged lid and being permanently mounted at the lower end of one of the fusee containers; and means for detachably mounting said fusee and torpedo containers upon said lantern as aforesaid.

2. A fusee and torpedo holding attachment for lanterns, comprising two elongated fusee containers with removable caps chained thereto, detachably mounted one each adjacent to and in vertical alignment with the opposite side bars of the lantern; a box-like torpedo container having a hinged lid and being permanently mounted at the lower end of one of the fusee containers; and a special catch rigidly joined to the lower end of each fusee container, said catch consisting of a heavy wire so bent that it may be turned into engagement with both the base ring and the side bar of said lantern, and a complementary swinging catch likewise extended from each fusee container at a spaced distance from said special catch, as means for detachably mounting said fusee and torpedo containers upon said lantern.

GRANT SELBY.
